ATTORNEY

UNITED STATES PATENT OFFICE.

MARCUS B. BEHRMAN, OF NEW YORK, N. Y., ASSIGNOR TO THE LOX SEAL CORPORATION, OF BROOKLYN, NEW YORK, A CORPORATION OF NEW YORK.

PILE WIRE.

Application filed March 17, 1926. Serial No. 95,249.

My present invention relates to pile wires, and has particular reference to that type of pile wire which is provided with means for detachably receiving and holding a cutting 5 blade.

One of the objects of the invention is the production of a pile wire of this character by means of a method which is not only extremely efficient in producing a staunch finished article, but which is of such extreme simplicity that the time and cost of manufacture is substantially reduced. Accordingly, a feature of the invention lies in shaping and manipulating the pile wire itself 10 for the purpose of producing the desired result.

The blade holding portion of the pile wire made in accordance with my invention is provided with a blade receiving channel 20 having one of its walls extended beyond the other to form the usual spoon or head with anchoring means in the holder for locking the blade in the channel and one of the features of my invention resides in the manner 25 in which the spoon or head of the blade is formed. This is herein disclosed as involving a distortion of one end of the pile wire so as to provide a spoon or head portion which is to one side of the longitudinal axis 30 thereof so as to have this spoon clear the channel in which the blade is to be received and preferably to have this spoon form a continuation of one wall thereof.

In the preferred method of carrying out 35 my invention the distortion of the end of the pile wire is effected by a rolling process.

Another feature of my invention is the manner in which the blade receiving channel 40 is formed in the pile wire and the relationship which such manner of formation bears to the manner in which the spoon is formed.

For the attainment of the foregoing objects and such other objects as may herein-after appear or be pointed out, I have illustrated one embodiment of my invention in 45 the accompanying drawings, in which

Fig. 1 is a perspective view of an end portion of a pile wire prior to any manipulation or shaping thereof;

Figs. 2 and 3 are elevational and plan views respectively of the pile wire shown in

Fig. 1 after the end portion has been dis- 55 torted;

Figs. 4 and 5 are views similar to Figs. 2 and 3 respectively after the channel has been formed;

Fig. 6 is a cross-sectional elevational view taken along the line 6—6 of Fig. 5 showing 60 in dotted lines the position which a blade will assume within the slot, and showing a preferred construction suitable for holding the blade in position;

Fig. 7 is a fragmentary plan view, show- 65 ing the rear portion of the slot illustrated in Fig. 6; and

Fig. 8 is a fragmentary elevational view showing a modification.

As my invention is particularly intended 70 for and is therein disclosed as embodying the blade holder and forming it from the end of a pile wire; I have illustrated in perspective in Fig. 1 an end 10 of the pile wire from which such holder is formed as will 75 shortly be described. The pile wire illustrated is of the conventional character em- 80 ployed and which is in the form of an elongated flattened bar of metal having the parallel side faces 10 and 11, and the parallel top and bottom faces 12 and 13 respectively, the latter being much narrower than the side faces as shown.

By exerting pressure to what may be termed the forward portion of the wire in 85 a direction perpendicular to the side faces 10 and 11, the forward portion of the wire is distorted so as to flatten and expand this end to thereby provide a head or spoon portion 14 which is not only wider than the side 90 faces 10 or 11 but which is considerably elongated in accordance with the predetermined requirements. Preferably, this distortion is effected by a rolling process, but it will be understood that any other process 95 may be employed. The compression or attenu- 100 ation is preferably such that the final thickness of the head or spoon portion is substantially less than one-half of the original thickness between the faces 10 and 11 for reasons that will shortly be understood.

This is clearly shown in Fig. 3. Moreover, the head is preferably constructed so that its rear face 15 is substantially flush with the face 11, while its front face 16 is substan- 105 tially parallel thereto. For reasons which

will be obvious to those skilled in the art, the head is preferably shaped peripherally to provide a point 17 and adjacent edges which are properly curved to facilitate the advancement of the end through the loom during its utilization. It will be understood that if desired, the head portion 14 may be distorted somewhat further, as for example, by curving the tip 17 or the rear portion thereof in a transverse direction, so as to facilitate further, the actual movement of the wire during its operation in a loom.

Referring now to Figs. 4 and 5, it will be observed that I provide a slot or channel 18 in the undistorted portion of the bar, and so positioned that it will lie substantially in a plane parallel to that of the head portion 14 and entirely to one side thereof. More particularly, the slot is provided, preferably by milling, in the top face 12 of the bar, extending to the required depth and of a width just sufficient to snugly accommodate a blade of the flexible wafer type. Where the slot is provided by means of a milling cutter, its rear end portion will decrease in depth gradually, as indicated at 19, in a manner which will be readily understood.

It will now be obvious that a blade of the usual construction and shape, having a substantially flat bottom edge and a rearwardly downwardly beveled upper or cutting edge, may be readily slid into the slot 18, either through the forward opening thereof, or downwardly through the top opening thereof, or in any direction between these two extremes. For the purpose of retaining the blade firmly in position, and at the same time permitting ready removal thereof so that the blade may be discarded and another blade inserted, I provide means integral with the head 14 and with the body portion of the bar, said means comprising preferably a struck-up tab 20 in the head portion 14, and one or more struck-up lugs or projections 21 in the rear portions of the channel walls. More particularly, the tab 20 is preferably constructed by making longitudinal cuts 22 and 23 and a transverse cut 24 connecting the former at their rear ends, that portion of the head 14 which is bounded by the cuts 22, 24, and 23 being then struck-up toward the axis of the channel so as to provide a rearwardly extending tab between which and the head 14 the forward portion of the blade may rest. In a preferred construction, the forward edge of the blade is provided with a U-shaped recess whose bottom edge may be made to rest snugly and firmly against the forward wall 25 of the tab 20.

For the purposes of retaining the rear end of the blade in firm, yet removable, position within the channel, I provide an overhanging portion in the channel beneath which the pointed end of the blade is received and in the drawings this is shown as attained by a

plurality of lugs or teats 21 struck inwardly into the channel, and constituting integral portions of the walls of the channel. These teats are preferably arranged along a line which will block the rear portion of the channel in a manner which provides an undercut recess underneath the lugs into which the rear attenuated portion of the blade may be inserted.

In Fig. 8, I have shown another method of providing the overhanging portion in the inner end of the channel. In this modification, I insert a wedge member 26, and preferably attach it, as by soldering, within the channel. The wedge member is of a suitable shape to effectively block the outer portion of the channel so that an undercut recess is provided into which the rear end of the blade may be inserted.

In order to insert the blade, the rear portion thereof is fitted under the lugs 21 or the wedge member 26, and thereafter the forward portion of the blade is flexed so that it will snap into place underneath the tab 20. The upper and lower walls of the closed edge 25 of the tab 20 will prevent the blade from moving upwardly or downwardly, and the undercut recess in the rear portion of the channel will have a similar effect. Moreover, the channel is made of such a length with respect to the blade that longitudinal movement of the blade will be prevented after it has been flexed and snapped into place. Removal of the blade is similarly simple, it being only necessary to release the forward end of the blade from underneath the tab 20, after which the blade may be withdrawn with great ease. It will here be observed that the provision of the channel entirely to one side of the head 14, so that one wall of the channel constitutes an integral continuation of the head, will not only lend additional support to the blade when it is in position, but will facilitate the unloosening of the blade by rendering the forward end of the latter easily accessible for the purpose of flexing.

It will thus be seen that I have provided a blade holder which may, if desired, be formed integrally with the pile wire, thereby greatly strengthening the latter, and which is of extremely simple construction, yet highly efficient in fulfilling its functions. It will also be observed that the method of construction is of such extreme simplicity that the cost of manufacture is very low. Furthermore, it will be seen that the finished article comprises only the original integral bar or wire, and no separately applied or attached parts or elements, the present method of manufacture rendering this feature possible, and thereby adding strength and rigidity to the finished device.

Many changes in the details herein de-

scribed and illustrated for the purpose of explaining the nature of my invention may be made by those skilled in the art without departing from the spirit and scope of the invention as expressed in the appended claims. It is therefore intended that these claims be interpreted as illustrative and not in a limiting sense.

While I have illustrated and described my blade holder as made from and integral with the pile wire, yet it will be understood that as far as some phases of my invention are concerned, this is not essential.

Having thus described my invention and illustrated its use, what I claim as new and desire to secure by Letters Patent is:

1. The method of making a blade holder adapted to form part of a pile wire, which comprises compressing an end portion of a bar in the direction of its width so as to provide a flattened head portion of increased area with respect to that of the portion which has been compressed.

2. The method of making a blade holder for a pile wire, which comprises attenuating an end of a bar to form a head, and forming a blade holding slot in the bar adjacent and open to said head and disposed along a plane entirely to one side of said head.

3. The method of making a blade holder adapted to form part of a pile wire, which comprises flattening an end of a bar to form a head having a thickness less than that of the bar, and slitting the bar adjacent to the

head to form a blade holding channel open 35 to the head and having walls of which one is an integral continuation of said head.

4. The method of making a blade holder for a pile wire, which comprises compressing an end of a bar to form a flattened head of a thickness substantially half of that of the bar, and slitting the bar adjacent to the head to form a channel which is so positioned as to receive a substantially flat blade lying in a plane substantially parallel to the 45 head said channel being open to and entirely on one side thereof.

5. The method of making a pile wire, which comprises flattening an end thereof 50 to form a head, and forming a longitudinal slot in the wire adjacent and open to said head and offset with respect thereto, whereby a blade may be inserted into said slot with its forward end disposed entirely 55 to one side of said head.

6. The method of making a pile wire having a blade holding portion, which comprises distorting an end of the wire to form a head, forming a longitudinal channel in the wire adjacent to the head and offset with 60 respect thereto, said channel being adapted to receive a flat blade, and striking up a portion of the head toward the plane of the channel to provide a tab adapted to engage the front edge of the blade.

In witness whereof, I have signed this specification this 11th day of March, 1926.

MARCUS B. BEHRMAN.
